CUFF ALIGNER

Charles Glenn Puckett, Harris Road,
South Fulton, Tenn. 42041

Filed Oct. 12, 1967, Ser. No. 8,965

Term of patent 7 years

U.S. Cl. D52—6
Int. Cl. D8—03

The figure of the drawing is a perspective view of a cuff aligner embodying my new design with the showing of a trouser leg in broken lines being depicted for illustrative purposes only.

I claim:

The ornamental design for a cuff aligner, substantially as shown and described.
